GARAGE DOOR CONTROL

Marion F. Burgett, Indianapolis, Ind.

Application March 7, 1934, Serial No. 714,441

5 Claims. (Cl. 268—62)

The object of this invention is to provide a mechanism connecting two swinging doors such as the large doors of a garage, that by manually swinging one of the doors the other door of the pair will be correspondingly opened or closed, and at different rates of travel whereby one will close sufficiently in advance of the other that the first door to close will not interfere with a joining strip carried by the other door.

Another object is to provide a simple and inexpensive device that will so lock and hold the doors in their open positions that they will be secure against accidental closing as by wind pressure or movement by other causes until unlocked.

I accomplish the above and other objects which will hereinafter appear, by the mechanism illustrated in the accompanying drawing, in which:

Fig. 1 is a detail in horizontal section of a garage showing the doors equipped with my invention, in open position in top plan view in full lines and in dash lines in near closed position.

Fig. 2 is a detail in elevation of the doors and operative mechanism, such as is shown in full lines in Fig. 1.

Fig. 3 is a detail on a larger scale of the left hand end of Fig. 2, showing parts in vertical section, and

Fig. 4 is a detail on a larger scale of the end of the locking lever showing its means of assembly with the spring and pull chain.

Like characters of reference indicate like parts in the several views of the drawing.

5 5 represent the wall of a garage at the door opening and 6 and 7 comprise a pair of doors which are hinged to the wall at the opening to swing about vertical hinge lines, in the usual manner.

Bolted to the inner side of the door 6 is a bracket 8, here shown as a semicircular plate, but the 40 shape may be varied, within the functional requirements of the cooperative mechanism of the device.

Pushing upon the bracket 8 is an end of a bar 9, which bar is swingingly attached to the bracket 45 by a bolt 10, here shown as double headed, but one end may be threaded and receive a nut in the usual manner. Bolted to the inner side of the door 7 is a bracket 11 to which is rigidly attached a bar 12, preferably extending to the rear at an acute angle from the door. The outer end of the bar 12 is pivotally attached to the outer 50 end of the bar 9. By reason of this bar, connection between the doors when one of the doors is manually swung on its hinges the other door will 55 be correspondingly swung. The length of the

bar 12 is preferably less than one third of the length of the bar 9, in order that the door 7 will move faster than the door 6, when one of the doors, preferably door 6 for the convenience of the operator, is manually swung on its hinges.

Secured to the outside of the door 6 at its outer vertical edge is a strip 13 which projects beyond the door 6 for the purpose of overlapping the door 7 and making a tight joint, and it is largely to cause the door 7 to close in advance of the door 6 to avoid interference with the strip 13 that the bars 9 and 12 are varied in length, as described.

I have here shown the bars 9 and 12 as made out of channel bar iron or steel for lightness in weight and cost and maximum strength, but do 70 not desire to be limited to bars of that construction.

Secured to the under side of the bar 9 near the bracket plate 10, here shown as by welding, is a metal strap 14, having a free end which projects 75 under the bracket plate to retain the bar in contact with the plate, and above the bar 9 is a bent latch bar 15, pivoted to the bar 9 at the angle of the latch bar. A short arm of the latch bar is normally raised by a spring 16 to contact the opposite long arm against the bar 9. The free end of this long arm extends within the area of the bracket plate 10 and terminates with a pin 17. The bar 9 and underlying strap 14 are formed with registering holes for the passage therethrough of the latch pin 17 and the bracket-plate 80 10 is formed with a hole 18 through which the pin 17, which is properly pointed for ready insertion, passes when the bar 9 is swung over the location of hole 18. The position of the hole 18 on its plate is such as to cooperate with the latch to lock the doors in the open position of the doors, as shown by full lines in Fig. 1. By the action 85 of spring 16 the locking operation is automatic, and to unlock the device, a link 19 is pivoted to the short arm of the latch bar 15 and extending through the spring 16 to retain the spring, passes through an opening in the bar 9 and has a chain 90 20 fastened to it. The chain forms a hand-pull to be grasped by the operator in releasing the latch.

The operation of my invention is so obvious and has been so completely described in connection with the foregoing as to negative the necessity for further description.

I do not desire to be limited by the exact construction shown nor any more than is required by the appended claims.

I claim:

1. In a door control, the combination with a 110

- pair of doors hinged to swing together in closing and apart in opening, one of said doors having a joint strip to overlap the other door when the doors are closed and a bracket plate attached to the door with the joint strip, of a bar supported upon and pivotally secured at one end to the bracket plate, and a second bar pivoted to the other end of the first bar and rigidly attached to the other door, the first bar being longer than the second bar to cause the doors to close without interference between the joint strip and the other door, said first bar carrying a latch to lock the bar to the plate. 80
2. In a door control, the combination with a pair of doors hinged to swing together in closing and apart in opening, one of said doors having a joint strip to overlap the other door when the doors are closed and a bracket plate attached to the door with the joint strip, of a bar pivotally secured at one end to the bracket plate, and a second bar pivoted to the other end of the first bar and rigidly attached to the other door, the first bar being longer than the second bar to cause the doors to close without interference between the joint strip and the other door, and a latch means carried by the first bar and pressed by a spring into engagement with a catch means in the plate for making the attachment of the first bar with the first door rigid. 85
3. In a door control, the combination with a pair of doors hinged to swing together in closing and apart in opening, one of said doors having a joint strip to overlap the other door when the doors are closed and a bracket plate attached to the door with the joint strip, of a bar pivotally secured at one end to the bracket plate, and a second bar pivoted to the other end of the first bar and rigidly attached to the other door, the first bar being longer than the second bar to cause the doors to close without interference between the joint strip and the other door, automatic latch means carried by the first bar and pressed by a spring into engagement with a catch means in the plate for making the attachment of the first bar with the first door rigid. 90
4. In a door control, the combination with a pair of doors hinged to swing together in closing and apart in opening, of a bracket plate rigidly attached to one of the doors, a bar pivotally secured at one end to the bracket-plate, a second bar pivoted to the other end of the first bar and rigidly attached to the other door, a bent latch lever pivoted to the first bar, a spring pressing an end of the latch bar away from the bar to which it is pivoted, the other end of the latch bar terminating within the area of the plate and carrying a latch pin, said bar to which the latch bar is pivoted and said plate having registering holes through which the pin passes when the pin reaches the location of the hole in the plate, and manually operated means to withdraw the pin. 95
5. In a door control, the combination with a pair of doors hinged to swing together in closing and apart in opening, one of said doors having a joint-strip to overlap the other door when the doors are closed, of a bracket-plate rigidly attached to the door having the joint-strip, a bar pivotally secured at one end to the bracket-plate, said bar having a tongue extending under the bracket-plate, a second bar pivoted to the other end of the first bar and extending from the rear thereto at an acute angle and rigidly attached to the other door, a bent latch-bar pivoted to the first bar, a spring pressing an end of the latch-bar away from the bar to which it is pivoted, the other end of the latch-bar terminating within the area of the bracket-plate and carrying a latch pin, said bar to which the latch-bar is pivoted, its underlying strap, and said plate, having registering holes through which the pin passes when the pin reaches the location of the hole in the plate, and manually operated means for withdrawing the pin. 100
